UNITED STATES PATENT OFFICE.

STEPHEN D. HUNTER, OF PHILADELPHIA, PENNSYLVANIA.

AUTOMOBILE WIND-SHIELD.

No. 873,047.

Specification of Letters Patent.

Patented Dec. 10, 1907.

Application filed July 11, 1907. Serial No. 383,272.

To all whom it may concern:

Be it known that I, STEPHEN D. HUNTER, a citizen of the United States, residing at Philadelphia, county of Philadelphia, and 5 State of Pennsylvania, have invented a new and useful Improvement in Automobile Wind-Shields, of which the following is a full, clear, and exact description, reference being had to the accompanying drawings, which 10 form a part of this specification.

The objects of my invention are, first, to so construct a two-part wind shield that the removable top part will be so secured to the stationary bottom part that the shield will 15 be virtually as strong and durable as a unitary shield of equal height; secondly, to so construct the parts that the upper part may be readily attached to and detached from the lower part; thirdly, to so construct the 20 parts that the upper part may, when detached, be readily supported by, and in rear of, the stationary lower part.

In the drawings: Figure 1 is a rear view of the wind-shield supported from the dash-board, the upper part being mounted in position above the lower part. Fig. 2 is a side view of the frame, engine casing and dash-board, with the dismounted upper part of the wind shield supported back of the lower part. 30 Fig. 3 is a longitudinal section through the tubular supports, when abutted, as in Fig. 1, and the plug and pin for securing the tubular supports together.

a is the frame of the motor vehicle, *b* the 35 engine casing, *c* the dash-board, *e* the tubes supporting opposite ends of the lower frame *x* of the two-part wind-shield, *f* the tubes supporting opposite ends of the upper frame *y* of the wind-shield.

40 The tubes *e* are supported from the dash-board by means of brackets *d*. Each frame is secured to its two supporting tubes by means of straps *g*. Into the upper end of each tube *e* is inserted a plug *h*. The upper end of 45 the plug is bored centrally and interiorly screw threaded to form a threaded end socket *i*. The plug *h* should be driven tightly into the tube *e* until the upper end of the plug is some distance below the upper end 50 of the tube. The plug, at its upper end, is tapered downwardly and inwardly to form a conical seat *k* at the outer end of the socket *i*.

Through each upper tube *f* extends loosely 55 a pin *m* whose contracted lower end *n* is screw-threaded and adapted to engage the threaded socket *i* in the plug *h* of the corre-

sponding tube *e*. The shoulder *o* above the contracted threaded end *n* is tapered and is adapted to engage the conical seat *k* when the pin is screwed into the plug. 60

When it is desired to detach the upper frame *y*, the pins *m* are unscrewed and the frame *y* dropped down, and the lower end of each pin *m* is screwed into the threaded socket in the bracket *s* secured to the fixed 65 lower half of the wind shield. The threaded socket in bracket *s* corresponds, in size and construction, to the threaded socket in plug *h*.

p is a tie-plate or washer through one end of which the pin *m* extends. When the 70 frame *y* is suspended alongside frame *x* as shown in Fig. 2, this end of the tie-plate is confined between the head of the pin *m* and the top of the corresponding tube *f* and the other end of the tie-plate *p* is extended over 75 the top of the corresponding tube *e* and is held in position by means of a short plug *r* which extends through the tie-plate and engages the threaded orifice *i* in the plug *h*. When the frame *y* is superposed upon the 80 frame *x* and the pin *m* screwed in position as shown in Figs. 1 and 3, the tie plate is again confined between the head of the pin *m* and the corresponding tube *f*, while the plug *r* is engaged with the threaded orifice in 85 the bracket *s* for safe-keeping. To support the shield with additional security and rigidity, braces *t* are employed, which are screwed to the frame of the vehicle and respectively to the two sides of the fixed lower 90 frame *x*.

Having now fully described my invention, what I claim and desire to protect by Letters Patent is:

1. A wind-shield for automobiles comprising a two part frame and two pairs of tubes between which the frames are respectively supported, plugs secured within the tubes of the lower frame and provided with threaded sockets having conical outer seats, and pins 100 extending through the tubes of the upper frame, said pins having contracted threaded ends and tapered shoulders at the junction of their bodies and said contracted threaded ends, said contracted threaded ends and 105 tapered shoulders being adapted to respectively engage the threaded orifices and conical seats in said plugs substantially as described.

2. A wind shield for automobiles comprising a two part frame and two pairs of tubes between which the frames are respectively

supported, plugs, having screw threaded end sockets, secured within the tubes of the lower frame, brackets, having screw threaded sockets, also secured to the tubes of the lower frame, and pins extending through the tubes of the upper frame, said pins having contracted threaded ends adapted to engage either the threaded sockets in the plugs when the upper frame is superposed upon the lower frame or the threaded sockets in the brackets when the upper frame is supported alongside the lower frame.

3. A wind-shield for automobiles comprising a two part frame and two pairs of tubes between which the frames are respectively supported, plugs, having screw threaded end sockets, secured within the tubes of the lower frame, brackets, having screw threaded sockets, also secured to the tubes of the lower frame, and pins extending through the tubes of the upper frame, said pins having contracted threaded ends adapted to engage either the threaded sockets in the plugs when the upper frame is superposed upon the lower frame or the threaded sockets in the brackets when the upper frame is supported alongside the lower frame, tie-plates through which said pins extend, and threaded plugs adapted to extend through said tie-plates and engage the threaded sockets in the plugs of the lower tubes.

4. A wind-shield for automobiles comprising a two part frame and two pairs of tubes between which the frames are respectively supported, plugs secured within the tubes of the lower frame and provided with sockets having conical outer seats, brackets provided with sockets having conical outer seats, and pins extending through the tubes of the upper frame, said pins having contracted ends and tapered shoulders at the junction of their bodies and said contracted ends, said contracted ends being adapted to engage either the sockets in the plugs when the upper frame is superposed upon the lower frame or the sockets in the brackets when the upper frame is supported alongside the lower frame.

5. A wind-shield for automobiles comprising a two part frame and two pairs of tubes between which the frames are respectively supported, plugs secured within the tubes of the lower frame and provided with threaded sockets having conical outer seats, brackets provided with threaded sockets having conical outer seats, and pins extending through the tubes of the upper frame, said pins having contracted threaded ends and tapered shoulders at the junction of their bodies and said contracted threaded ends,

said contracted threaded ends being adapted to engage either the sockets in the plugs when the upper frame is superposed upon the lower frame or the sockets in the brackets when the upper frame is supported alongside the lower frame, tie-plates through which said pins extend, and threaded plugs adapted either to extend through said tie-plates and engage the threaded sockets in the plugs of the lower tubes when the upper frame is supported alongside the lower frame or to engage the threaded sockets in the brackets when the upper frame is superposed upon the lower frame.

6. A wind-shield for automobiles comprising a two part frame and two pairs of tubes between which the frames are respectively supported, plugs secured within the tubes of the lower frame and provided with sockets, brackets having similar sockets located alongside the lower tubes at a distance from their upper ends substantially equal to the length of the upper tubes, and pins extending through the upper tubes and adapted for engagement with the sockets in the plugs when the upper frame is superposed upon the lower frame and with the sockets in said brackets when the upper frame is dismounted.

7. A wind-shield for automobiles comprising a two part frame and two pairs of tubes between which the frames are respectively supported, plugs secured within the tubes of the lower frame and provided with sockets, brackets having similar sockets located alongside the lower tubes at a distance from their upper ends substantially equal to the length of the upper tubes, and pins extending through the upper tubes and adapted for engagement with the sockets in the plugs when the upper frame is superposed upon the lower frame and with the sockets in said brackets when the upper frame is dismounted, threaded plugs adapted for engagement with the sockets in the brackets when the upper frame is superposed upon the lower frame and with the sockets in the plugs of the lower tubes when the upper frame is dismounted, and tie-plates, through which both the pins and the last-named plugs are adapted to extend to connect the upper ends of the two pairs of tubes when the upper frame is dismounted.

In testimony of which invention, I have hereunto set my hand, at Philadelphia, on this 24th day of June, 1907.

STEPHEN D. HUNTER.
